UNITED STATES PATENT OFFICE.

LAWRENCE LEE SCHAUER, OF CINCINNATI, OHIO, ASSIGNOR TO THE CINCINNATI BICKFORD TOOL COMPANY, OF CINCINNATI, OHIO, A CORPORATION OF OHIO.

FRONT HAND ELEVATOR FOR ARMS.

Application filed June 12, 1921. Serial No. 477,145.

To all whom it may concern:

Be it known that I, LAWRENCE LEE SCHAUER, a citizen of the United States, and residing at Cincinnati, in the county of 5 Hamilton and State of Ohio, have invented a new and Improved Front Hand Elevator for Arms, of which the following specification is a full disclosure.

This invention is directed to improvements in the means for adjustably supporting the table of a drilling-machine at various heights with respect to the bed and it proposes a simple and self-contained structural arrangement whereby the elevation 15 may be manually effected by the user when standing immediately adjacent the table.

In drilling-machines, as in all other species of machine tools, the arrangement must be such as to satisfy many desideratums and 20 much difficulty was frequently experienced in effectively meeting all of such requirements on account of the fact that many of them are more or less structurally incompatible. In the case of the elevating-mechanism for the table-supporting arm of a 25 drilling-machine, some species of irreversible transmission is habitually employed in order to prevent the weight of the table from causing the shafts to rotate and permit the 30 table to descend. In certain types of drilling-machines, a power-driven nut-and-screw is conventionally resorted to for this purpose, but, in the case of smaller machines (where the elevating power is derived from 35 the user) it has been found desirable to accomplish the elevation by means of a rack-and-pinion. One reason for this is that a 40 rack is more compatible, with the provision of means for permitting the arm to swing about the post, than a nut-and-screw because the screw must be journaled at its ends so as to permit of a rotation and it must also be capable of bodily revolving about the axis of the column. In the case of a 45 rack, it is sufficient merely to make provision for the bodily revolution of the rack; inasmuch as it does not rotate about its own axis and, consequently, a much simpler structure can be employed. A rack-and-pinion, however, is not irreversible and, accordingly, it is essential to interpose, between the hand-actuated shaft and the 50 pinion engaging the rack, a species of irreversible transmission device. Usually the irreversible device takes the form of a worm- 55

and-gear, and this unit has, heretofore, been mounted directly on that portion of the arm which circumscribes the post or column and it has, heretofore, been essential for the user to walk to the column whenever it became 60 desirable to adjust the height of the arm. That structure not only had the objection of inconvenience, as will be perceived, but it likewise produced a very unsightly machine; inasmuch as the irreversible unit required considerable space and had to be located in a casing having the appearance of a protuberance formed on the column-end of the arm. A further difficulty was, in the 65 circumstances, encountered by reason of the fact that the circumscribing portion of the arm was habitually split in the plane of its longitudinal axis and this not only created difficulties in the assembling of the arm on the post but it also gave rise to much trouble 70 in respect to assembling the irreversible unit and the co-operating rack-and-pinion. It is very desirable to inspect these parts at infrequent intervals; but such inspection was 75 virtually prohibited by the aforesaid inconvenient conventional arrangement.

This invention, however, proposes an arrangement (A) whereby the irreversible unit will be located on the forward end of the arm underneath the table, where there 80 is ample unoccupied space, so as to relieve the column-circumscribing end of the sleeve from the unsightly protuberance; (B) to enable the user to raise and lower the table 85 supporting arm without moving from his normal working-station; (C) to permit the 90 pinion, the worm and the gear each to be readily assembled for purpose of inspection or replacement without disturbing the assembly of the arm on the post and without 95 necessitating the removal of the rack; (D) to achieve the foregoing results in a manner entirely compatible with an improved arrangement with respect to the arm and the post facilitating the employment of a box-type arm having its post-circumscribing portion split transversely to its longitudinal axis in combination with an easily removable 100 end-cap; thereby permitting the rack and other parts very readily to be assembled with 105 relation to the post.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is a side-elevation of a drilling-machine embodying this improvement. Fig. 2 is a plan of the table and arm assembled on the post. Fig. 3 is a front elevation of the machine.

Referring to the drawings, a column 2 is, by means of its foot 29, shown secured to a suitable base or bed 1; the column having an upper portion 2 for supporting a drill-carrying arm (not shown) which is usually adapted to be bodily raised and lowered on slide-ways 40. The portion of the column between the part 2 and the foot 29 is devoted to the support of the work-table arm 4 which is capable of being raised and lowered thereon, and is also capable of being swung laterally, partially or wholly, to one side to accommodate different classes of work. The table supporting arm, herein designated by 4, is preferably constructed in the manner disclosed in detail in the co-pending application of David C. Klausmeyer, filed May 20, 1921, Serial Number 471,074, as well as certain other features hereinafter briefly described but to which no claim is herein made; save in combination, as indicated by the appended claims.

The rear end of this arm 4 circumscribes the post 3 and consists of a semi-circular seat 5 and a cap 8 which is securely bolted thereto by means of a shaft 21 operating through lugs 6 and 9; the shaft 21 extending (parallel with the longitudinal axis of the arm) through the bearing 22 and terminating underneath the table with a squared end, whereby it may be manually manipulated. It will be noted that the split 12 in the arm is in a plane transverse to the longitudinal axis of the arm; thereby enabling the cap 8 very easily to be removed and permitting the employment of a box-type arm so as to secure great rigidity in the supporting of the table.

The table indicated by 18 is provided with an annular seat 19 resting on a corresponding rigid seat provided by the forward end of the arm, and said table has a hub 20 which extends downwardly through a vertical hole 13 provided by the free end of the arm. In order for the table to be clamped rigidly in place, the forward end of the arm is provided with flexible wings 14 and 15 which may be drawn together by the bolt 16 when operated by the handle 17.

Further rigidity is secured by means of

an instrumentality in the nature of an adjustable travelling support comprising the elements 23 and 24; said parts having been fully described in the aforesaid application.

The elevation of the arm is achieved through an instrumentality which comprises a rack 25 that, at its inner surface is slightly curved in conformity with the periphery of the cylindrical column 3, so that it may be bodily carried about such periphery as the arm is swung one way or another. This rack is contained in a vertically elongated channel 26 provided in part by the arm proper and in part by the cap 8, as appears best by Fig. 2; making it a simple manner to assemble parts in the course of manufacture. The rack is located between the upper and lower annular shoulders 27 and 28 which prevent it from moving longitudinally; said rack normally resting firmly on the lower shoulder 28 which is in the nature of a bearing or race-way.

Co-operating with the rack 25 is a pinion 33; this pinion being journaled in the boss 31 provided by the flange 10 of the cap 8. The pinion is secured to the end of a shaft 32 that extends forwardly through its journal in the boss 30. This provides an adequate bearing for the parts mentioned and at the same time enables the shaft 32 easily (when disconnected at its forward end) to be moved rearwardly to expose the pinion without dismounting any of the parts heretofore mentioned.

The irreversible unit is contained within a casing 34 (either bolted to, or forming a part of, the forward end of the arm) underlying the table and consequently is located out of the way. This irreversible unit comprises a worm-wheel 36 that is secured to the forward end of the shaft 32; said shaft being journaled at 35 and provided with a nut 37 which may be removed to release the worm-wheel and permit the shaft to be axially withdrawn. A worm 39 is transversely journaled within the casing 34 in mesh with the worm wheel 36; said worm being mounted on a shaft 38 which protrudes laterally and is provided with a squared end, whereby it may be manually rotated by the user when stationed immediately adjacent the table. This enables him to raise and lower the table without going to the rear.

It will thus be perceived, that this invention, in a simple and direct manner, has achieved the objects and advantages set forth in the foregoing and but few parts are necessitated by its structure.

Without further analysis, the foregoing will so fully reveal the gist of this invention that others can, by applying current knowledge, readily adapt it for various utilizations by retaining one or more of the essential characteristics of either the generic or spe-

cific aspects of this invention, and therefore, such adaptations should be, and are intended to be, comprehended within the meaning and range of equivalency of the following 5 claims.

Having thus revealed this invention, I claim as new and desire to secure the following combinations and elements, or equivalents thereof, by Letters Patent of the 10 United States:

1. A machine-tool combining a column; a box-type arm extending transversely from said column and mounted to rotate and to slide axially thereon; a work-support rotatably mounted on, but bodily fixed to the free end of said arm; means to clamp said work-support in adjusted positions; means to clamp said arm non-rotatively upon said column; means to cause axial movements 15 of said arm on said column; means located adjacent the free end of the arm and in fixed position with respect to said work-support for actuating said arm clamp and said elevating means; and an adjustable support 20 for said arm, said support being carried by the free end of the arm adjacent the actuating means for said clamp and arm elevating means.

2. A machine-tool combining a column; a 25 box-type arm extending transversely therefrom and mounted to rotate and to slide axially thereon; a work-support carried by the free end of said arm; means to clamp said work-support in adjusted position; means to clamp said arm non-rotatably upon said column; means to cause axial movements of said arm on said column; and adjustable means carried by said arm to support the free end thereof, said several means 30 embodying controlling devices grouped upon the forward end of said arm, under said work-support, and there operable manually in the respective adjusted positions of said arm and work-support.

3. A drilling-machine combining a cylindrical column; an arm radiating therefrom and having its rear end in the form of a sleeve split transversely to the length of said arm; a work-support located upon the 45 forward end of said arm, means embodying reduction gearing and located at the forward end of said arm for enabling it to be manually elevated; and means accessible at the forward end of said arm for manually 50 clamping it on said column.

4. A drilling-machine combining a cylindrical column; an arm radiating therefrom and having a semi-circular rear-end bearing on said column; a semi-circular cap 55 bolted to the rear-end of said arm, the plane

of division between said cap and arm extending transversely to the length of said arm, said parts providing a recess cut by the plane of division; a rack bodily rotatable with said arm and located in said 65 recess; a clamp for constricting the other side of said cap, and means manually operable from the front end of said arm for elevating it through the instrumentality of said rack and for clamping it to said column. 70

5. A machine-tool, combining a column; a box-type arm extending transversely therefrom and having a sleeve mounted to rotate and to slide axially on said column; a rack confined by, and revoluble bodily with, said 75 sleeve; a shaft of substantial length journaled at one end in a bearing afforded by said sleeve and at its other end in a bearing carried by the outer end of said arm, said shaft having on one end a pinion journaled in said sleeve engaging with said rack and operable to cause axial movements of said arm; and reduction gearing at the forward end of said arm and connecting with said shaft, having manual operating devices 80 also at said forward end, whereby said arm may be elevated, and retained in its various 85 positions, against gravity.

6. A machine-tool combining a column; a box-type arm extending transversely therefrom and formed at its rear end with a split sleeve adapted to rotate and to slide axially on said column, an arm-elevating device associated with said split sleeve at one side of said column; an arm-clamping device 90 connected with said sleeve at the opposite side of said column; a first shaft journaled lengthwise of said arm at one side thereof and operatively connected with said arm-elevating device; a second shaft journaled 95 lengthwise of the arm at the side thereof opposite said first shaft and affording means for operating said clamping device; a work-support mounted adjustably on the free end of said arm; means to clamp said 100 work-support in adjusted positions; adjustable means for supporting the free end of said arm; a third shaft journaled in said arm transverse to said first shaft; a speed-reduction gearing between said first and 105 third shafts; said second and third shafts, work-support clamping means, and arm-support adjusting means being so constructed and arranged as to be manually adjusted 110 from a single position adjacent the forward end of the arm.

In witness whereof, I hereunto subscribe my name.

LAWRENCE LEE SCHAUER.
